GRINDING MACHINE

Norman B. Chace, Jr., Detroit, Mich., assignor
to Ray Day Piston Corporation of Detroit, De-
troit, Mich., a corporation of Delaware

Application July 28, 1932, Serial No. 625,327
Renewed February 15, 1937

7 Claims. (Cl. 51—46)

This invention relates to grinding machines, particularly machines for grinding round or cylindrical objects, such for example, as pistons. One of the important features of the invention is to provide an improved machine of the foregoing general character which is capable of producing for example, pistons having peripheral walls or outer surfaces which are "out-of-round." A further feature of the invention is to provide a machine capable of grinding pistons in an improved manner so as to provide a pair of opposed walls which have a cylindrical contour or outer surface and a second pair of opposed walls adjacent the wrist pin bosses having an outer surface or contour which is "out-of-round" and preferably tapered longitudinally of the piston. Another feature of the invention is to provide a method of grinding a piston so that two of the outer walls of the piston are cylindrical and the other two opposite walls are "out-of-round." Another object of the invention is to provide a method whereby the entire peripheral wall of the piston may be ground, but wherein two opposite faces only of the piston wall are ground slightly out-of-round, and in which the grinding is accomplished on a taper longitudinally of the piston.

Other objects and advantages of the invention will appear from the following description and appended claims when considered in connection with the accompanying drawings forming a part of this specification. In said drawings:

Fig. 1 is a fragmentary front elevation of a grinding machine showing one form of my invention applied thereto.

Fig. 2 is a side elevation taken substantially along the line 2—2 of Fig. 1, looking in the direction of the arrows.

Fig. 3 is a sectional view, partly in elevation, taken substantially along the line 3—3 of Fig. 2, looking in the direction of the arrows.

Fig. 4 is a section taken substantially along the line 4—4 of Fig. 3.

Fig. 5 is a side elevation, partly in section, taken substantially along the line 5—5 of Fig. 1, looking in the direction of the arrows.

Fig. 6 is a sectional view, partly in elevation, taken substantially along the line 6—6 of Fig. 5.

Fig. 7 is a longitudinal section, partly in elevation, taken substantially along the line 7—7 of Fig. 5.

Fig. 8 is a sectional view, partly in elevation, taken substantially along the line 8—8 of Fig. 7, looking in the direction of the arrows.

Fig. 9 is a section taken along the line 9—9 of Fig. 7.

Fig. 10 is an elevational view, somewhat exaggerated, of a piston made in accordance with the method of my invention; and

Fig. 11 is a section taken substantially along the line 11—11 of Fig. 10.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring now particularly to the drawings, in which like reference characters designate corresponding parts in the several views, I have shown a portion only of one of the standard grinding machines to which my invention is applied. In the present instance, the machine is provided with work holders which support the work at opposite ends and permit it to be rotated relatively to a rotatable longitudinally and laterally adjustable grinding wheel or element. The machine shown is adapted for use in grinding cylindrical or round objects, such for example as pistons, to produce a piston having an external wall or periphery, the contour of which is out-of-round at the two opposite faces adjacent the piston pin bosses. The mechanism embodying my invention is adapted to be detachably and interchangeably mounted upon the machine and comprises, as shown, separate units adapted to support the work at opposite ends, rotate the work, and impart to the opposite ends of the work an oscillatory motion, during rotation, which oscillation is independent at the opposite ends of the work. The mechanism of my invention is associated and timed to operate in conjunction with the driving or operating mechanism of the grinding machine.

Referring to Fig. 1, 15 designates, as a whole, a portion of the base or supporting structure of a standard grinding machine, and 16 is a bed plate or table upon which the work actuating units 18 and 19 are adjustably mounted. At the left end of the machine an upright bracket or housing 17 is supported upon the base and provides a bearing for a main drive shaft 20. At 21 is shown a driven shaft by which one end

of the work is rotated. Below this shaft and in substantially the same plane, an additional driven shaft 22 is located, said last named shaft having an enlarged portion 22a. The shaft 21 is driven 5 by the shaft 20 through the medium of intermeshing gears 23 and 24, whereas shaft 22 is driven from shaft 21 by means of cooperating sprockets and a drive chain, shown as a whole at 25. Adjacent the sprocket and chain construction a relatively large bearing 26 is mounted, 10 through which the shaft 22 extends.

At 27 there is shown, as a whole, one of the work supporting and rotating members, the reference character 28 designating as a whole, the 15 other work support, the supports forming a part of the present invention. Cams 29 and 30 are mounted at spaced points upon the enlarged portion 22a of the driven shaft. The cam 29 cooperates with a roller 32 rotatably mounted 20 in the forked end of an arm 31. The cam 30 cooperates with a roller 34 which is mounted in the forked end of an arm 33. These arms and rollers are best shown in Figs. 2 and 5. A spring 31a is attached at one end to the arm 31 and 25 at its opposite end to the bed plate of the machine and serves to apply tension to the arm to maintain the roller 32 in contact with the cam 29. A similar tension spring 37 serves to hold the roller 34, carried by the arm 33, in contact with 30 the cam 30.

Referring particularly to Fig. 2, 31b designates as a whole, a post or rod extending above and below the axis of oscillation of the arm 31. Tension springs 31c are connected with the opposite 35 ends of the post and are also attached to the face of the unit 18 to apply additional tension to the arm to resist its rocking or oscillating movement and any tendency of the roller to move away from the cam, as fully described 40 hereinafter.

Referring now particularly to Fig. 3, the inner 45 end of the shaft 21 is provided with an enlargement 21a and a tapered end portion 21b, the purpose of the taper being to fit within an eccentric bushing to be described below. The work support 27 is rotatably connected with the shaft 21 through the medium of a connecting link or shaft 40 and a pair of universals 41 and 42 which are connected with the shaft end 21b and a sleeve 43 which telescopes over the bushing, respectively. The inner i. e., exposed end of the sleeve is reduced to provide a substantially cylindrical portion 43a and has a forward extension 43b upon which is detachably mounted, by means of a pin 43c, a shiftable block or member 45 which is adapted to fit within the space between the piston pin bosses of a piston shown as a whole at P. The cylindrical portion 43a carries a frusto-conical member 44 upon which the lower 50 end of the skirt portion of the piston rests when the work is in position to be ground by the wheel G. W. Located within the sleeve 43 and mounted upon the end 21b of the driven shaft, is an eccentric bushing 46 having a flange 46a. A bearing, such as a ball or roller bearing assembly 47 surrounds the shaft 21 and is interposed between the enlargement 21a and the flange 46a of the eccentric bushing. The opposite end of the bushing engages a similar ball or roller bearing assembly 48 which is interposed between the eccentric bushing and the portion 43a of the sleeve. The parts are preferably held together by a plate 49 and a plurality of bolts 50. It will be seen that these bolts pass through the 55 annular portion of the arm 31, thus clamping

said arm to the flange 46a of the eccentric bushing. Suitable packing is provided between the shaft and the several parts as shown in Fig. 3. A packing compressing device is also provided which comprises a substantially cylindrical portion 51 and a flange 52. The bolts 50 serve to maintain the device in place and permit it to be tightened when and if necessary. 5

It is to be noted that the universal connection between the driven shaft end 21b and the work support 27 permits the axis of the work support to be offset with respect to the axis of the shaft. In practice, these axes are offset with respect to one another approximately one quarter inch, although the distance may be varied in accordance with the requirements of the machine and the particular work to be performed. Any suitable lubricating device may be used to lubricate the parts, there being shown, merely by way of example, a gravity type lubricator 53. 10

Referring now particularly to Figs. 7, 8, and 9 wherein the other work support 28 is shown in detail, the unit or housing 19 is provided with a bore 19a in which is located a sleeve 55 which projects beyond the inner face of the member 19. The sleeve has a key-way or slot 55a formed therein and is held against rotation by a locking key or member 56 secured in place by cap screws 57. The work support comprises a cylindrical portion 58 having an enlarged end portion 58a 15

and an eccentric bore adapted to receive the tapered portion 65a of a stub shaft 65, the latter being located within the tapered bore of the fixed sleeve or support 55. The portion 65a is provided with oil grooves 65b. A work engaging and supporting center or pin 66 extends into a bore formed in the portion 58 and terminates just short of the flat end of the tapered shaft portion 65a. The shaft 65 has an enlargement 62 which engages a ball or roller bearing assembly 60 located within the portion 58a. The parts are held together in position upon the shaft 65 by a closure plate 100 and a series of bolts 59. The portion 33a of the arm 33 is secured to the work support and is clamped in place against the member 58a by the bolts 59, so that rocking or oscillatory movement of the arm will impart a corresponding movement to the member 58 relative to the shaft 65. The end or tip of the center or pin 66 is adapted to engage in a recess formed in the head of the piston P to support that end of the piston. 20

It is desirable at times to adjust the position of the supporting center or pin 66 so as to bring the center line or axis of this pin to coincide with the center line or axis of the supporting cone 44, in order that the piston may be ground straight on the faces at right angles to the piston bosses PB, or to adjust the supporting center or pin 66 to bring its center line out of line with the center line of the cone 44, so as to produce tapered surfaces at right angles to the pin bosses PB as well as a tapered surface adjacent the pin bosses. 25

Referring to Fig. 5, the arm 33 comprises a forward member or portion 33 and a rear member 33a, these members having respectively upper extensions or lugs 33b and 33c. The forward portion 33 has a bifurcated or forked rear extension 33d and a lower rear extension or bifurcated portion 33e. The latter portion provides a pivotal connection between the parts by means of bolt 33f. The upper bifurcation or fork 33d engages the portion 33a and is provided with a locking device having a handle for actu- 30

ating it, said locking device being shown as a whole at 33g.

To effect relative adjustment of the portions 33 and 33a, the locking device is released and 5 the adjusting screw 35 is manipulated to separate or bring together the upward extensions 33b and 33c. This causes both members 33 and 33a to revolve around the bolt 33f, and the member 33a, in turn, is revolved around the center line of 10 the member 65, thus swinging member 58, which holds the center or supporting pin 66 away from the grinding wheel or toward it, dependent upon which way the screw 35 is manipulated.

Separation of the upper extensions 33b and 33c 15 swings the work away from the grinding wheel and manipulation of the screw 35 so as to move the upper extensions 33b and 33c toward each other swings the center 66 toward the grinding wheel. Each of these members is provided with 20 a lug on its top face, which lugs are interconnected by means of a tension spring 36, the purpose of which is to draw lug 33c against the end of screw 35.

Referring particularly to Figs. 10 and 11, there 25 is illustrated in these figures a piston made in accordance with the invention. It will be noted that the broken line B designates the outer wall or surface of the piston skirt prior to grinding. The full lines A indicate the face or outer surface 30 after the grinding operation has taken place. It will be noted that the taper grinding is done on the two opposed walls adjacent the wrist pin bosses PB so that these two opposed walls are slightly out-of-round with respect to the opposite walls or portions C, and the straight grinding is done on the two opposed sides at right angles to the piston pin walls. As is well known, the head of a piston expands to a greater extent than the skirt thereof due to the excessive heat 35 to which the head is subjected. It is further known that the expansion takes place in the direction of the piston pin bosses, so that the piston, under heat, assumes a substantially oval shape. Such expansion causes the piston to bind 40 or "freeze" in the cylinder. It is known that by grinding the opposed surfaces adjacent the piston pin bosses, the reduced diameter at these points compensates for the expansion of the piston. With respect to the effect of heat upon 45 the skirt, it is known that the heat transmitted to the skirt from the head is dissipated to a greater degree at points removed from the head in the direction toward the lower end of the skirt. The top portion of the skirt adjacent the head expands to a greater degree than the lower portion thereof. Moreover, this expansion is greatest at the opposed faces or walls adjacent the piston pin bosses. For this reason, it is desirable to grind these particular faces of the piston 50 out-of-round on a taper longitudinally of the piston, with the taper increasing toward the head end of the piston.

Operation of the machine

55 As shown by Fig. 1, a piston P is positioned between the work supports 27 and 28 which engage it and maintain the piston in position adjacent the periphery of the grinding wheel G. W. Inasmuch as the grinding wheel per se forms 60 no part of the present invention, except that it is used in connection with my improved mechanism for grinding articles out-of-round, it is not deemed necessary to show or discuss it more in detail. It will suffice to say that the grinding wheel is driven by suitable mechanism con- 65

nected with the drive mechanism for the other parts of the machine, and that it is adjustable longitudinally relatively to the work, i. e. lengthwise of the machine, and also laterally, i. e. crosswise of the machine from front to back and vice versa, so that it may be moved, first into contact with the work, and then longitudinally along the face or periphery of the work to perform the grinding operation. 5

It is well known that it is highly desirable, as 10 set forth above, to provide a piston having an outer surface or peripheral wall which is out-of-round, and that it is further desirable that the out-of-round portions of the piston be located on the opposite faces adjacent and surrounding 15 the piston pin bosses. Accordingly, I have provided the foregoing improved mechanism for supporting and rotating the work and for further imparting to the work an oscillatory motion independently at opposite ends of the work to permit 20 the grinding wheel to grind two opposed faces of the piston wall adjacent the piston pin bosses out-of-round and the remaining two walls round or cylindrical, during each revolution of the piston; and to further regulate and control the oscillatory or shifting movement of the opposite ends of the piston so as to produce, on the two opposed ground faces which are out-of-round, a taper 25 which extends longitudinally of the piston. As shown, this taper occurs on opposite faces adjacent 30 the piston pin bosses and extends from the lower end of the skirt toward the head of the piston, increasing toward the head end. It is, however, entirely within the scope of my invention to extend the aforesaid grinding operation to include 35 the head portion also of the piston, if and when desirable. It is also within the purview of my invention to impart to a piston or any similar round or cylindrical object, a grinding operation 40 which produces a pair of out-of-round portions or faces on any two surfaces which are opposed to one another. The out-of-round portions of the piston merge with the cylindrically ground portions thereof in such a manner that the junction 45 of the dissimilarly ground portions is not discernible. 45

In practice, a piston is inserted between the members 27 and 28, with the skirt portion thereof engaging the frusto-conical member 44 and the head portion engaging the end or tip of the center 50 or pin 66. After the piston is in position, with the block or member 45 fitting snugly within the space between the piston pin bosses, power is applied to the shaft 20 through the medium of the power belt 122 and pulley 121 to rotate the work support 27 and the piston relative to the work support 28 at the head end of the piston. Referring now particularly to Figs. 3 and 7, which show in detail the work supporting members, the frusto-conical member 44 and the block 45 are 55 rotated on an axis which is offset with respect to the axis of rotation of the driven shaft 21, this offset relation being permitted by reason of the universal connection 40, 41, 42 between the shaft and the work support. When the shafts 20 and 21 are rotated, the shaft 22 is likewise rotated, there being suitable reduction provided by means of the chain and sprockets 25, one of which members is adjustable on the shaft to properly time the cams and to impart to the several shafts the proper speed of rotation. As the shaft 22 rotates, the cams 29 and 30 are likewise rotated and inasmuch as these cams engage, respectively, the rollers 32 and 34 carried by the arms 31 and 33, it will be seen that these arms 70 75

are given a rocking motion. The arm 31, being connected with the eccentric bushing 46, causes an oscillation of said bushing about which the sleeve 43 is rotating, thus causing a shifting or off-center oscillation of the work support 27 and likewise the skirt end of the piston. The tension springs 31a and 31c (Fig. 2) serve to maintain the roller 32 in constant engagement with the cam 29 to produce a constant and accurate oscillation of the eccentric bushing and work support. The arm 33a is directly connected with the other work support 28 and as the cam 30 is rotated by the shaft it engages the roller 34 and imparts to the arm a similar rocking movement which causes an oscillation of the work support 28. It is to be noted that the axis of the pin 66 is offset with respect to the axis of rotation of the shaft 65, thus causing an off-center or crank-like oscillation or shifting of the work support 28 and the head end of the piston. During the foregoing action the grinding wheel is being rotated constantly to grind the entire periphery or outer faces of the piston to produce a pair of out-of-round faces or portions adjacent and surrounding the piston pin bosses, and another pair of opposed cylindrical faces or portions at right angles to the bosses. The cams 29 and 30, as shown, are dissimilar, since, where it is desirable to provide the piston with a pair of out-of-round sections or portions which are tapered, the degree or amount of oscillating motion imparted to the work support 27 is materially less than that imparted to the work support 28. If, however, opposed out-of-round sections or faces which are not tapered, are desired, the two cams 29 and 30 would be substantially identical.

While I have described above and illustrated in the drawings, merely by way of example, a shaft or spindle which rotates on a fixed axis and a work holder which is positioned off-center with respect to the spindle and is driven from it by a universal connection, together with an adjustable eccentric for varying the oscillatory movement of the work holder, it is contemplated by my invention that the work spindle itself may be mounted to rotate within an eccentric sleeve, which eccentric sleeve is adjustable in substantially the same manner by means of a cam, as above described. In such instance, the work holder will be oscillated by virtue of a fixed off-center connection with the shaft or work spindle, rather than through a variable off-center connection by virtue of the universal joints or connection herein shown. The variation of the oscillatory movement would be obtained by the cam oscillating the eccentric within which the work spindle rotates instead of the eccentric on which the work holder rotates.

I claim:

60 1. In a machine for grinding a cylindrical piece of work, such as a piston, the combination of a rotary grinding member for grinding the periphery of the work, a pair of work holders for supporting opposite ends of the work in position to be operated upon by said grinding member, means for rotating the work through one of said work holders, means for relatively moving the work and grinding member in a longitudinal direction, cam means for imparting an oscillatory movement to both of said work holders thereby to grind two opposite faces of the work out-of-round, and eccentric means for varying the oscillatory movement of one work holder relatively to the other work holder.

75 2. In a machine for grinding a cylindrical piece

of work, such as a piston, the combination of a rotary grinding member for grinding the entire circumference of the work, a pair of work holders for supporting opposite ends of the work in position to be operated upon by said grinding member, means for rotating the work through one of said work holders, means for relatively moving the work and grinding member in a longitudinal direction, cam means for imparting an oscillatory movement to both of said work holders thereby to grind two opposite faces of the work out-of-round, and eccentric means for varying the oscillatory movement of each work holder.

3. In a machine for grinding a cylindrical piece of work, such as a piston, the combination of a rotary grinding member for grinding the entire circumference of the work, a pair of work holders for supporting opposite ends of the work in position to be operated upon by said grinding member, means for rotating the work through one of said work holders, means for relatively moving the work and grinding member in a longitudinal direction, cam means for imparting an oscillatory movement to both of said work holders thereby to grind one pair of opposed faces of the work out-of-round, and adjustable eccentric means for varying the oscillatory movement of each work holder and one relatively to the other.

4. In a machine for grinding a cylindrical piece of work, such as a piston, the combination of a rotary grinding wheel for grinding the periphery of the work, a pair of work holders for supporting opposite ends of the work in position to be operated upon by said grinding wheel, means for rotating the work, cam means for oscillating each work holder to shift the work relative to the grinding wheel twice during each revolution of the work, thereby to grind two opposed faces of the work out-of-round, and means for varying the oscillatory movement of one work holder relatively to the other.

5. In a machine for grinding a cylindrical piece of work, such as a piston, the combination of a rotary grinding member for continuously grinding the periphery of the work, rotary work holders for independently supporting opposite ends of the work, and mechanism comprising a driven cam and an oscillatable arm carrying a roller with which said cam contacts for shifting the work twice during each rotation thereof relatively to the grinding member to grind predetermined opposed faces of the work cylindrically and other faces of the work out-of-round on a taper extending longitudinally of the work, said taper occurring only on the two opposed out-of-round faces of the work.

6. In a machine for grinding a piston, the combination of a rotary grinding member for continuously grinding the periphery of the piston, rotary work holders for independently supporting opposite ends of the piston, and mechanism including a driven cam and a rocking arm provided at its free end with a cam engaging roller for independently shifting opposite ends of the piston twice during each rotation thereof relatively to the grinding member to grind predetermined faces of the circumference of the piston cylindrically and other faces of the piston out-of-round on a taper extending longitudinally of the piston only at the out-of-round faces thereof.

7. In a machine for grinding a cylindrical piece of work, such as a piston, the combination of a rotary grinding wheel for grinding the entire circumference of the work, a pair of work holders for supporting opposite ends of the work in posi-

tion to be operated upon by said grinding wheel, means for rotating said work holders, and means including a driven cam and an oscillatable arm provided with a roller with which said cam contacts for oscillating each work holder to shift the work relative to the grinding wheel twice during

each revolution of the work at equally timed intervals, thereby to grind two opposed faces of the work out-of-round and the other faces of the work cylindrical.

NORMAN B. CHACE, JR. 5
